UNITED STATES PATENT OFFICE.

ISIDOR KITSEE, OF PHILADELPHIA, PENNSYLVANIA.

TELEGRAPHY.

No. 863,853.

Specification of Letters Patent.

Patented Aug. 20, 1907.

Application filed April 24, 1907. Serial No. 369,969.

To all whom it may concern:

Be it known that I, ISIDOR KITSEE, a citizen of the United States, residing at Philadelphia, in the county of Philadelphia and State of Pennsylvania, have 5 invented certain new and useful Improvements in Telegraphy, of which the following is a specification.

My invention relates to an improvement in telegraphy.

Its object is to enable persons versed in the art to 10 transmit simultaneously two messages from opposite directions over the line of transmission.

This system, on account of its simplicity and ease of handling, lends itself readily to railroad work, wherein a series of stations are connected to one line. The system 15 is also applicable to general telegraph work, and if only two terminals of the stations are inserted, the system may also be employed in submarine cable work.

The drawing represents in diagram a telegraphic circuit embodying my invention.

20 1 is the line of transmission; 2 and 3 are the batteries inserted in the line at the terminals, both batteries consisting of equal cells and connected to the line in opposition as to each other. The line is grounded at 4.

25 The drawing illustrates the line to contain the three stations A, B and C. One station is a duplicate of the others and similar devices are similarly designated. Each station comprises the electro-magnet 5 which may be a simple sounder or any other electro-magnetic translating device.

30 In all respects, this device may be similar to the device now in use, with the exception that the coil thereof, here designated by the numeral 6, is provided at different points with outside contacts, here designated by the numeral 7. In proximity to these contacts is the switch 8 connected with the interposition of transmitting means to the ground 4. These transmitting means are illustrated in the drawing as to consist of the lever 9 and the stationary point 10 of a usual transmitting key, but it is obvious that instead of the manual 35 transmitter, any of the well known transmitters may be substituted.

The operation of this arrangement is as follows: As long as the line is idle, that is, none of the stations are working, the energy from 2 being opposed by the energy 45 from 3, no current will flow over the line, but as soon as the line is grounded on any other point, then the energy from both the batteries 2 and 3 will flow each over parts of the line and will return by the additional ground.

It is supposed that the operator at station A desires to 50 transmit a message. If he would connect the line directly to the ground either before or after the device 5, then either one or the other of the currents from 2 or 3 will flow through the device and the same will answer to the flow of this current, but as it is desired that the 55 home device should remain neutral to the home trans-

mission, I have provided means so that the influence of the current from the far off station should be neutralized by the influence of the current from the home station, and this means consists therein that the grounding of the line is not made directly, but is made through 60 part of the coil of the receiving device 5; and as the ratio of neutralization varies, I have provided means whereby a greater or lesser part of the coil 6 of the receiving device 5 may be connected to the ground and thereby the home current be made to flow through a 65 greater or lesser number of convolutions of said coils. When the operator at A transmits a message and, therefore, connects one or the other of the contacts 7 through the interposition of the key to the ground, a path is established for the current of the far off station, which 70 travels or flows through the whole coil of the instrument of the far-off station through the whole line to the station which is transmitting this message. Here the current flows only through that part of the coil which is not grounded and hence to energize the core to a certain 75 polarity. But as the current from the home station travels through that part of the coil which is grounded and as the flow of this current is in opposition to the flow of the current from the far-off station, it is obvious that if the effects of these two currents are equalized, 80 the home instrument will not answer.

It is understood that the number of cells has to vary in accordance with the length of the line and the desired effect; so also has the type of the receiver to vary in accordance with requirements; so also the number 85 of contacts coming from the coil of said receiver.

It is advised, that the person in charge of the station should, before the commencement of a message or better at the beginning of every working day, balance his coil, so as to know with what particular contact the 90 switch should be connected to give the best results.

As long as only the operator of one station, say the station A, as illustrated in the drawing, transmits a message, a current will flow from the battery 3 over the line in the direction of the unfeathered arrow, will flow 95 through one part, here shown as the upper part, of the coil of device 5 of said station and at the same time a current will flow from the battery 2 through the other part of said coil, here shown as the lower part, and, as said above, the magnetizing effect of both coils will 100 be in opposition as to each other and will, therefore, neutralize each other; but as soon as simultaneously with the depression of the key at station A, the operator at station B depresses his key, both of the batteries 2 and 3 are short circuited, so to speak, and there current 105 will not flow over the line, but will only flow through the home instrument. The home instrument will, therefore, respond to this current, as long as both keys are depressed; but as soon as one or the other of said keys is opened, then the neutralization takes place. 110

To persons versed in the art, it will be apparent that with such arrangement, the duplexing of the line can easily be carried out commercially and the cumbersome arrangements of artificial lines and alike devices 5 are eliminated.

I stated above that this system can also be practiced with submarine cables and, indeed, in submarine cables, the simultaneous transmission of message in opposite directions, if each of the two stations is equipped 10 with an arrangement as described and illustrated, is easily accomplished.

Having now described my invention, what I claim as new and desire to secure by Letters Patent is:-

1. In combination, a telegraphic line, terminal batteries 15 for said line, said batteries in opposition as to each other, terminal and intermediate stations for said line, each station provided with an electro-magnetic device inserted in series in said line, and means for each station to ground a greater or lesser part of the coil of said electro- 20 magnetic device.

2. In a system of telegraphy wherein two sources of current are connected to the line in opposition as to each other, means to make the home instrument immune to the home transmission, said means comprising adjustable

means to connect part of the coil of the home instrument 25 to the return.

3. A system of telegraphy comprising a line of transmission, a source of current for each terminal thereof, a series of stations for said line, a receiving device for each station, and means to connect part of the coil of the receiving device to the return, in accordance with the characters to be transmitted. 30

4. Means to duplex a telegraphic line, said means comprising an electro-magnetic device inserted in said line, two sources of current in opposition as to each other connected to said line, and adjustable means to connect part of the coil of said receiving device to the return. 35

5. In duplex telegraphy, a line of transmission, two or more stations therefor, an electro-magnetic device inserted in the line for each station, and means dependent 40 on the operation of the transmitting means to cause two currents to simultaneously flow each to one part of one common coil, and means to vary the proportion of the coil for the flow of each current in a manner, so as to neutralize their magnetizing effect. 45

In testimony whereof I affix my signature in presence of two witnesses.

ISIDOR KITSEE.
